KOLOMAN BRULL, OF BUDAPEST, AUSTRIA-HUNGARY.

ELECTRICALLY-OPERATED REVERSING-GEAR.

1,080,044.

Specification of Letters Patent.

Patented Dec. 2, 1913.

Application filed February 27, 1912. Serial No. 680,287.

To all whom it may concern:

Be it known that I, KOLOMAN BRÜLL, mechanical engineer, residing at Budapest, in the Empire of Austria-Hungary, have invented certain new and useful Improvements in Electrically-Operated Reversing-Gear, of which the following is a specification.

My invention has reference to a reversing gear which is arranged between any driving shafts and permits of reversing the rotary direction of one of the said shafts while the other shaft continues to rotate always in the one and the same direction.

The essential feature of the invention consists in the arrangement of an electrical auxiliary motor which switches the gear into the three main positions, the rotation to the left, the stoppage and the rotation to the right. This is effected rapidly, uniformly but very smoothly without effort and without the exertion of any special skill on the part of the attendant. This arrangement is of special importance for cranes as well as for grab winches the many manipulations of which necessitate constant attention and dexterity.

The great simplicity of the present invention is owing to the fact that all the manipulations are effected by a single electrical element, capable of passing into three fundamental positions, in combination with a controlling shaft. This electrical element can be switched over into one of the said three positions from the controller of the main motor (electric driving engines being more particularly concerned) or by means of a switch for weak currents.

I will now describe my inventions as applied to a grab winch, and in which:

Figure 1. is a plan view of the winch in which the auxiliary motor together with the coupling levers is shown turned through 90°. Figs. 2-4 show constructional details in front elevation and longitudinal section respectively. Fig. 5. shows a diagram of the main and auxiliary controller cylinders, the connections between them and their connection with the switch board and the main and auxiliary, motors. Fig. 6. shows a diagram of the controller cover and of the switching direction. Fig. 7. shows the four directions in which the controller lever is moved to cause the desired movement of the mechanism. Fig. 8 is a detail view of an actuating means on the motor shaft 20.

A motor 1, generally a series motor, drives an intermediate shaft 5 by means of a bevel wheel 2 meshing with wheels 3 and 4 mounted on the shaft 5 as soon as one of two coupling cones 6 and 7 is made to engage with a corresponding counter-cone of bevel wheel 3 or 4. The motion of the intermediate shaft 5 is transferred to the closing drum 9 of the grab by means of the cog wheels 11 and 12. The drum 9 is keyed upon its shaft, while the drum 10, which serves for the opening of the grab is loosely mounted on the same shaft, but can be clutched to the shaft by the friction clutch 14 rendered operative by means of a weight Q₁ Figs. 2 and 3. The brake 13 is rigidly connected with the drum 10, this brake is released by means of the servo-motor 17 which is preferably a brake motor owing to the fact that upon the rotation of this motor in the corresponding direction the cam *x* mounted on the operating shaft 18 lifts the brake weight Q₂ Fig. 4. The ratchetless thrust bearing band brake 16 is mounted on the shaft 5 the toothed wheel 12 being keyed to the plate 23. The plate 23 can be removed from the plate 16 by reason of the provision of screw threads on the shaft 5. In addition to the cam *x* two other cams — *y*, *z* — are mounted on the operating shaft 18 of the brake motor 17, one of them *y* serving to control the clutch 14, the other *z* serving to release the band brake 16. A plate 15 is mounted in front of the drum 10, this plate is retained against rotation by means of bolts 24 mounted on the drum 10 and is displaced along the shaft on screw threads and pressed against the drum 10. The reversing gears 2-7 are also controlled by a second cam shaft 20 driven by an electromotor 19. The cam shaft 20 is drawn into a definite middle position by means of a spring or weight, this position corresponding to the disengagement of the friction cones 6 and 7. The opposite strokes of the cam shaft 20 attainable by the opposite starting of the motor 19 (which drives the shaft 20 preferably by intermediation of suitable gear) serves for connecting up reversing gear 6 or 7 corresponding to the hoisting or lowering movement of the drums 9 and 10 which it is desired to occasion.

The transmission of the movement from the cams 21 to the coupling and brake levers can be effected in any desired manner, for example as shown in the drawing by means of rollers 22 mounted directly on the levers.

It is evident that this arrangement in the case described occasions considerable saving in time and power by dispensing with the necessity of reversing the heavy masses of the rotating hoisting engine without placing any physical strain whatsoever on the driver of the crane who is already fully occupied with the complicated manipulation of the grab. The frequent breakage of the teeth of cog wheels occasioned by the lack of skill of the driver is avoided because once the weight has been correctly adjusted the switching into one of the three fundamental positions is effected with absolute regularity. Similar advantages and similar manner of working can also be attained, by means of the electric auxiliary motor described, with other reversing gear of all kinds.

I will now describe the controller-device in connection with the switch board and the motors. Fig. 5. shows the diagram of the main and auxiliary controller cylinders, the connections between them and their connection with the main and auxiliary motors. The basis for drafting the diagram of the connections is the fact that: 1. when hoisting and lowering the open or closed grab-bucket both auxiliary motors must be switched-on simultaneously in the same rotary direction. 2. during the opening only the newly added auxiliary motor 19, which effects the reversing is brought into the position corresponding to the lowering without, however, starting the auxiliary motor 17 already previously employed for operating the grab-bucket. Now in order to be able to switch-on the four working phases,— starting the main motor under no-load, switching the mechanism to hoisting, lowering and opening, there are two switch rollers (which can be arranged in the same or separate casings) effected with a single lever by means of universal control. The main cylinder is a simple, multi-stage (10 steps) starting, but not reversing, cylinder with two auxiliary contacts (H); the second cylinder is a single stage reversing cylinder with altogether only eight contacts. These cylinders are so coupled together, that one of the four working phases respectively correspond to the four switching directions of the control lever, as shown in the controller diagram. Assume that all motions both of the hoist motor and the gear are stopped. The filled grab suspending from the drum of the gear is now to be lowered. At first the hoist motor will be sped up by rendering the scale 0, 1 . . . 10 of the main cylinder, (Figs. 5 and 6), operative, putting the controller lever gradually over the turning-point 10 (Fig. 7) from its horizontal position into a vertical one in the plane marked by the line starting-opening (Fig. 7). In this position of the controller lever only the

hoist motor is influenced as the movable contacts —10— of the main cylinder (Fig. 5) lead current from the switch board through contacts A, B, C, D and the corresponding wires only to the hoist motor. All resistances in the circuit of the hoist-motor's rotor are now switched off and the motor is running therefore at full speed. The brake motor 19 as well as the brake motor 17 (Fig. 1) being uninfluenced, remain in their zero position which corresponds to the disengagement of both clutches 6 and 7 and the gear doesn't take any part therefore in the movement of the hoist motor. The driver, putting now the controller lever over its turning-point out of its vertical position into the direction marked "Lower" (Fig. 7) turns by the corresponding wheels of the universal-joint of the controller cylinders the auxiliary cylinder in the direction "Lower," (Fig. 5 and Fig. 6), and connects the corresponding movable contacts of this cylinder up to the network. By contacts E, F, G, I and wires T (Fig. 5) current will be conducted to the brake motor 17 (Fig. 1) which swinging out of its middle position in one direction, releases the band-brake 13 and engages the clutch 14, by the corresponding rotation of the cams X and Y (Figs. 2, 3 and 4). The brake 16 remains applied during this motion of the brake motor 17, as when it was in the zero position of the latter.

By contacts, K, L and wires U (Fig. 5), the brake motor 19 (Fig. 1) will be influenced and it will swing out of its middle position into the corresponding direction. One of the clutches 6 and 7 (say 6) will be engaged by the corresponding weight owing to the fact that upon rotation of the cam shaft 20 this weight may descend freely and will be able to close the clutch. The movement of the hoist-motor 1 will be then transmitted by the engagement of clutch 6 to the drum 9 and by the clutch 14 to the drum 10 in a sense, which will correspond with the lowering direction of the grab. Both drums move downward with the same velocity and the closed grab is lowered. If the grab should be opened, the driver puts the controller lever from its actual position with one movement, back to its vertical position, and with a second movement turns it in the plane marked by line "Starting-opening" into the direction "Open". By the first movement of the controller lever the auxiliary cylinder will be switched off, therefore the entire grab gear disconnected from the hoist-motor (which continues its running), and is stopped in a minute, and by the second movement of the controller lever the main cylinder (Fig. 5 and Fig. 6) will be turned farther to the point "Open". In this position of the main cylinder the movable contacts A, B, C, D remain further in

connection with their corresponding fixed contacts and lead current to the hoist motor, as described above, but besides this, the movable contacts H come in connection with 5 their fixed contacts and lead current through wires V and U to the brake motor 19. It is readily seen that the direction of current will be the same in the wires U now as before, when connected with the contacts K, 10 L, and therefore the brake motor 19 will engage (by turning the cams 21, Fig. 1), the same clutch, as before, that is, 6. The brake motor 17, being only connected to the auxiliary cylinder which is now switched off, remains 15 uninfluenced; that is, in its zero position which corresponds with the checking of the brakes 13 and 16, and the disengagement of clutch 14. The movement of the hoist motor will be transmitted only to the 20 drum 9, which will move downward, while the drum 10, holding the opening rope, is checked by the applied brake 13, the jaws of the grab being open. During the opening of the grab the disk 15, which is retained 25 against rotation by the bolts 24, moves from the checked drum 10 and its distance from the latter exactly corresponds in a certain ratio to the length of the closing rope coiled down from drum 9. Assuming, now, that 30 the opened grab should be lowered farther to the point where it can seize material, then the driver puts the controller lever with one movement back to its vertical position and from here with a second movement again 35 into the position of lowering (Fig. 7). By the same swinging out of both brake motors 17 and 19 and action of the operating cams x , y , z and 21, as described before, both drums 9 and 10 will move downward with 40 the same velocity and the opened grab will be lowered.

When the grab has attained the point where it shall grasp material, the driver puts the controller lever from its actual position marked "Lower", into its vertical position. Both brake-motors 17 and 19 are switched off the network and return to the zero position. The grab gear will consequently be disconnected from the hoist-motor and checked against all unintended motions by the applying of the brakes 13 and 16. Now, in order that the grab should seize material and be hoisted, the driver puts the controller lever from its middle 55 and vertical position in the plane marked by line "Lowering-hoisting" (Fig. 7) into the direction "Hoisting". Besides the existing connections A, B, C, D of the main cylinder the following contacts of the auxiliary cylinder will be connected up to the network: M, N, O, P, R, S from which M, N, O, P lead current through wires T to the brake motor 17, while R and S are contacts of the current of brake motor 19. It is 60 obvious from the connections of the auxil-

iary cylinder that the directions of the currents in wires T and U are now reversed against the direction, when the lowering part of the auxiliary cylinder was switched on. Both brake motors will swing out, therefore, in the opposite direction as before when lowering was going on, the result of which will appear in the engagement of the clutch 7, in the releasing of the brakes 13 and 16, and the disengagement of clutch 14. 70 The same movement of the hoist-motor will be transmitted by clutch 7 in a reversed sense to the drum 9, that is to say, this drum will move in the hoisting direction. The drum 10 remains for a while stationary. In 80 this period the jaws of the grab will be closed. At the moment the grab is closed the disk 15 which was coming nearer to the drum 10 during the closing of the grab, engages with this drum, drives it and coils the 85 unstretched opening cable up to this drum. Both drums move with the same velocity upward and consequently the filled grab will be hoisted.

The object of the employment of the thrust bearing brake is the regulation of speed during the lowering and the opening of the grab. As mentioned before, the band-brake part 16 of the thrust bearing brake is applied during this motion owing 90 to the fact that in the zero position of the cam shaft 18 as well as when it is swung out into the position corresponding to the lowering movement of the grab, the cam z doesn't actuate the lever of the band-brake 95 16, the band of which standing therefore under the tension of the brake weight, checks the disk 16. If the descending load obtains a greater speed than that imparted to it by the hoist motor during these operations of the grab, the disk 23 will be 100 pressed against the checked brake 16 and the difference in the kinetic energies of the descending load and the main motor will be absorbed by the friction caused on the front 105 of disk 16.

Concerning the actuating of the weight Q, it should be remarked that it is in its lowest position when the brake motor is uninfluenced, zero position, and upon the rotation of the cam shaft 20 in either direction this weight will be lifted. After having carried out the desired operation with the grab and after having switched off the brake motor, this weight compels the cam shaft 110 115 and by it the brake motor to return into its zero position.

It is not necessary to block the free movement of the control lever (on a ball-head) by guides. The brake motor can be dispensed with and as a substitute therefor two solenoids may be used.

Having now described my invention I declare that what I claim is:

1. In combination with a pair of grab 130

- controlling drums, a driving shaft having operating connections for driving said drums, an electric motor having its armature shaft perpendicular to said driving shaft, a bevel gear on said armature shaft, a pair of bevel gears loose on said driving shaft and meshing with the gear on said armature shaft, clutches for clutching said gears to said driving shaft, and an electric motor for operating said clutches.
2. In combination with a pair of grab controlling drums, a driving shaft having operating connections for driving said drums, an electric motor having its armature shaft perpendicular to said driving shaft, a bevel gear on said armature shaft, a pair of bevel gears loose on said driving shaft and meshing with the gear on said armature shaft, clutches for clutching said gears to said driving shaft, bell crank levers operatively connected with said clutches, a rotary shaft having cams for actuating said
- 10 15 20

bell crank levers, and an electric motor for driving said shaft.

3. In combination with a pair of grab controlling drums, a shaft, operating connections therefrom for driving said drums, an electric motor for driving said shaft, reversing gearing interposed between said driving motor and shaft, an electric motor, with connections therefrom for controlling the operation of said reversing gear, and a controller for the grab hoist drums, provided with three scales corresponding to the three grab operations, said scales meeting at a zero point which has to be crossed by the controller lever between each two operations, substantially as described.

In testimony whereof I affix my signature in presence of two witnesses.

KOLOMAN BRÜLL.
